PROCESS FOR RECOVERY OF AROMATIC HYDROCARBONS

John W. Waldron, Philadelphia, Pa., assignor, by
mesne assignments, to Allied Chemical & Dye
Corporation, a corporation of New York

Application October 12, 1940, Serial No. 360,864

8 Claims. (Cl. 202—57)

1

This invention relates to a process for recovering as a substantially pure product an aromatic hydrocarbon of the benzene series from oils containing it and containing other hydrocarbons, including olefins, boiling from the oil in the same temperature range as the aromatic hydrocarbon boils therefrom.

Numerous hydrocarbon oils are known which contain aromatic compounds of the benzene series in varying proportions together with substantial proportions of olefinic hydrocarbons (by which term I refer to both olefins and diolefins). For example, gasoline fractions obtained in the treatment of petroleum frequently contain substantial proportions of benzene, toluene and/or xylene together with olefins, paraffins and naphthenes. Oils of petroleum origin having a considerable content of aromatics of the benzene series may be treated by well known selective solvent processes, for example extraction with liquid sulfur dioxide, to produce fractions rich in aromatics but which will still contain substantial amounts of olefinic, paraffinic and naphthenic hydrocarbons. A considerable portion of these hydrocarbons cannot be completely separated from the aromatic constituents by fractional distillation because of the closeness of the boiling points of non-aromatic constituents of the oil to the boiling points of the aromatic constituents or because the non-aromatic constituents form constant boiling mixtures with the aromatic. While the aromatic constituents of light oils produced by the gasification of coal ordinarily may readily be separable and recovered as the substantially pure individual aromatic constituents, in some cases these light oils contain non-aromatic oils, including olefins, which are but difficultly separable from the aromatic constituents of the oil. Also, synthetic hydrocarbon mixtures produced by various catalytic processes may contain aromatic constituents of the benzene series accompanied by olefins and other non-aromatic hydrocarbons difficultly separable from the aromatic constituents.

For many purposes to which aromatic hydrocarbons are put it is desirable to use as pure a material as may be available economically. For example, toluene is largely used for the production of TNT, for which purpose a so-called "nitration grade" of toluene is now preferred. While

2

toluene products containing substantial proportions of certain hydrocarbons other than toluene can be nitrated, the mono-nitro compound made from them must be purified prior to complete nitration. This materially increases the cost and complexity of the process for making TNT. Furthermore, even though toluene containing substantial quantities of certain other materials is sometimes used for nitration, this is only because the difficulties of preparing a pure toluene have outweighed the disadvantages of using the impure toluene for the production of explosives. Direct fractional distillation will not effect a recovery of pure toluene from oils such as enumerated above and in many cases will not give fractions of suitably high toluene content or free from materials which even in small concentrations adversely affect the nitration of the toluene or the nitrated product.

20 Azeotropic distillation of hydrocarbon oils such as described above in the presence of an added azeotropic agent which forms azeotropes with the several non-aromatic hydrocarbons in the mixture, i. e., the olefinic, naphthenic and paraffinic hydrocarbons, having lower boiling points than the aromatic constituent of the oil or its azeotrope, will effect a selective separation from the oil of the non-aromatic hydrocarbons which, in the absence of the azeotropic agent, boil from the oil in the same temperature range or at lower temperatures than the aromatic hydrocarbon boils therefrom. By azeotropically distilling the oil to accomplish this separation, the residue of the azeotropic distillation may be subjected to a non-azeotropic, fractional distillation to remove hydrocarbon constituents, aromatic or non-aromatic, of higher boiling range than the desired aromatic constituent. Or by first fractionally distilling the original oil in the absence of added azeotropic agent to recover a cut containing the desired aromatic together with the other hydrocarbons boiling from the oil up to temperatures only a few degrees above the boiling point of the desired aromatic constituent and then azeotropically distilling such a cut under suitable conditions, an oil residue substantially consisting of the desired aromatic hydrocarbon may be obtained.

40 I have found, however, that in thus azeotropically distilling oils containing aromatic hydro-

50

carbons and substantial quantities of olefinic hydrocarbons, it is frequently very difficult to obtain sufficiently complete separation of the olefinic from the aromatic constituents for the aromatic product to have the purity desired, especially when it is to be nitrated. I have found this difficulty is encountered most frequently in treating oils in which the ratio of olefins to aromatics is relatively high. In distilling such refractory oils, the degree of fractionation both in non-azeotropic and in azeotropic distillation, becomes of critical importance, and the degree of fractionation necessary for recovery of aromatic hydrocarbons in good yield and substantially free of non-aromatic hydrocarbons may be so great as to make the operation uneconomical or to exceed the facilities available at a given plant. The alternative, with fractionation equipment inadequate for securing high yields of relatively pure aromatic hydrocarbons, is to sacrifice yield to purity by taking off as overhead or intermediate cuts distillate containing considerable amounts of the desired aromatics as well as the non-aromatics which are to be removed from the oil to leave an aromatic residue of the desired purity.

On the other hand, although it is known that treatment of an oil with concentrated sulfuric acid will remove olefinic hydrocarbons, such treatment is not satisfactory as a preliminary to azeotropic distillation in the present case. In the presence of concentrated sulfuric acid olefins condense with aromatic hydrocarbons and the resultant products are removed from the oil with the acid. Consequently, when an oil containing a high ratio of olefins to aromatics is treated with strong sulfuric acid, a large part or even all of the aromatics may be removed from the oil. The yield of aromatics in a recovery operation following such treatment would be reduced by the amount of aromatics so removed.

It is an object of my invention to provide a process whereby a substantially pure aromatic product may be recovered without undue loss from an oil containing it and containing like-boiling, non-aromatic hydrocarbons, including substantial amounts of olefins. (In this specification and in the appended claims, the term "like-boiling, non-aromatics" is used to denote the non-aromatic hydrocarbons of an oil which boil therefrom in the same temperature range as the aromatic hydrocarbons of the oil boil therefrom, and thus these like-boiling, non-aromatics are difficultly separable or inseparable from the aromatics by a non-azeotropic fractional distillation of the oil.) It is an object of my invention to provide a process for the recovery from such olefin-containing oils of a relatively pure aromatic constituent by a process suitable for large scale economical recovery of the aromatic.

I have discovered that without excessively rigorous fractionation olefins may be selectively removed together with other non-aromatic hydrocarbons from refractory oils such as those described by means of an azeotropic distillation, and that such a distillation may be carried out to the point where the residue contains a good yield of the desired aromatic hydrocarbon practically free of paraffins and naphthenes, and the olefin content of the residue has been reduced to such an extent that the olefins may be removed by sulfuric acid with much less loss of aromatics than if the oil containing olefins is treated with sulfuric acid prior to azeotropic distillation.

My invention comprises distilling a hydrocarbon oil containing aromatic and like-boiling, non-

aromatic hydrocarbons, including a high ratio of olefins to aromatic, with rectification of the vapors evolved in distilling the oil, in the presence of a material forming low boiling azeotropes with the non-aromatic constituents of the oil. By this azeotropic distillation the non-aromatic hydrocarbons are selectively distilled out, leaving a residue enriched in aromatics. This azeotropic distillation of the oil is continued until the residue of the distillation contains at least one aromatic hydrocarbon, no more than 10 parts by weight of like-boiling paraffinic and naphthenic hydrocarbons to each 90 parts of said aromatic hydrocarbon, and a part only of the olefins present in the oil which is distilled. The aromatic hydrocarbon of the residue of this azeotropic distillation, accompanied by the olefins not removed from the residue by the azeotropic distillation, is washed with concentrated sulfuric acid in amount sufficient to remove from the aromatic hydrocarbon substantially all of the olefins. By this process a product is obtained containing one or more aromatic hydrocarbons from which the like-boiling, non-aromatic hydrocarbons have been separated to a desired degree. The oil subjected to the azeotropic distillation step of my process may contain hydrocarbons boiling above and/or below the boiling range of the aromatic hydrocarbon present in the oil which is to be recovered in the residue of the distillation. Lower boiling hydrocarbons (aromatic or non-aromatic) will be taken over as distillate in the azeotropic distillation. Higher boiling hydrocarbons which may still remain with the desired aromatic product may be removed therefrom by non-azeotropic distillation to give a product containing the desired aromatic hydrocarbon of increased purity.

The process of my invention is of particular advantage when the hydrocarbon oil containing an aromatic and like-boiling, non-aromatic hydrocarbons which is to be azeotropically distilled, contains olefins in amount such that the numerical ratio of the percent of aromatic hydrocarbons in the oil to the bromine number of the oil is less than 250.

In determining the ratio of the percent aromatic hydrocarbons in the oil to the bromine number, the aromatic content of the oil may be determined, for example, by the method of specific dispersion (described in Industrial & Engineering Chemistry, Analytical edition, 11 (1939), 614-624), due care being taken to remove or allow for interfering substances if present in the oil. The bromine number of the oil may be determined by Francis's method (described in Industrial & Engineering Chemistry, 18 (1926), 821-822).

Further, in treating an oil containing olefins in accordance with the process of my invention, the oil preferably is subjected to two distillations; one the above-described azeotropic distillation and the other a fractional distillation (non-azeotropic). In the azeotropic distillation the like-boiling paraffinic and naphthenic hydrocarbons and a portion of the olefinic hydrocarbons are selectively distilled out leaving an oil residue enriched in the desired aromatic hydrocarbon, containing no more than 10 parts by weight of the like-boiling naphthenic and paraffinic hydrocarbons to each 90 parts of the desired aromatic hydrocarbon, and containing a part of the olefins. In the non-azeotropic fractional distillation, which may either precede or follow the azeotropic distillation, the aromatic constituent which is to be recovered by the process is separated from

higher boiling hydrocarbons and lower boiling hydrocarbons, if any are present. The combined effect of these two distillations is to separate an aromatic hydrocarbon product largely or entirely freed from higher and lower boiling hydrocarbons and from like-boiling paraffin and naphthene hydrocarbons and freed from like-boiling olefinic hydrocarbons to such an extent that the original olefin:aromatic ratio is substantially reduced.

The aromatic hydrocarbon recovered in the residue from the azeotropic distillation, accompanied by a reduced amount of olefinic hydrocarbons, is subjected to treatment with concentrated sulfuric acid, preferably of about 88% to 100% H₂SO₄ strength, in amount sufficient to remove from the aromatic hydrocarbon substantially all of the olefinic compounds. When the non-azeotropic distillation of the hydrocarbon oil follows the azeotropic distillation, the treatment of the aromatic hydrocarbon fraction with sulfuric acid preferably follows the non-azeotropic distillation. By the two distillations and treatment with sulfuric acid, the aromatic hydrocarbon may be recovered as a product of 90% or higher purity and substantially free of olefins. This process may readily be operated to produce toluene of high commercial purity, e. g., 99-100% and substantially free of olefins, which meets all requirements for "nitration pure" toluene.

While my process may be carried out with the non-azeotropic distillation step following the azeotropic distillation of the original aromatic oil fraction, for convenience and economy in operation I much prefer to first non-azeotropically distill the original oil, taking off a cut or fraction containing the aromatic constituent which it is desired to recover from the oil separated from the higher and lower boiling hydrocarbons. By first fractionally distilling the aromatic oil and then azeotropically distilling only that cut in which the desired aromatic constituent is concentrated, the quantity of oil treated in the azeotropic distillation and the amount of azeotropic agent distilled per unit of product made are reduced and the azeotropic distillation made more economical and more readily operable to recover the desired aromatic constituent accompanied by a part of the olefins of the original oil, which olefins are then removed by the sulfuric acid treatment.

In the processes of my invention the sulfuric acid treatment removes from the aromatic oil fraction the olefin hydrocarbons contained therein. The thus treated aromatic fraction may be neutralized with an alkali and redistilled.

My invention is of particular importance as a means for recovering pure toluene from oils containing it together with other hydrocarbons. The examples described below and illustrative of the invention show its application to the recovery of toluene from petroleum oils.

The accompanying drawing illustrates diagrammatically an apparatus suitable for carrying out the processes of the examples. With reference to the drawing, the numeral 1 indicates a still provided with a heater 2 and connected with a rectification column 3 and a condenser 4 for the vapors leaving the top of the column. By means of valves 5 and 6, condensate flowing from condenser 4 is divided in controlled proportions. One part of the condensate is returned through pipe 7 to the top of column 3 and refluxed in contact with the vapors rising in the column. The other portion of the condensate is with-

drawn through pipe 8. Two receivers 9 and 10 are connected to pipe 8 through valve-controlled branch pipes 11 and 12 so that the condensate drawn off through pipe 8 may be divided and distributed as described below to the two receivers.

Receiver 10 is connected by a pipe 13 controlled by valve 14 with a second still 15. Still 15, like still 1, is provided with a heater 16, a rectification column 17, a condenser 18 and pipes 19 and 20 controlled by valves 21 and 22 for return of determined proportions of condensate from condenser 18 to the top of column 17 and withdrawal of another portion of the condensate through pipe 20. Pipe 20 connects with valve-controlled branch pipes 23 and 24. Two separators 25 and 26 are connected to the respective branch pipes 23 and 24. Each of these separators is provided with a water inlet pipe 27 and 28, respectively. Each separator is provided with a liquid withdrawal pipe 29 and 30, respectively, for removal from the separator of a top oil layer and withdrawal pipes 31 and 32, respectively, for withdrawal of a bottom aqueous liquid layer. Pipe 30 leads to a liquid treating tank 33 in which liquid withdrawn from separator 26 may be agitated with sulfuric acid introduced to tank 33 through a pipe 34. Tank 33 contains any conventional means, not shown in the drawing, for intimately mixing the sulfuric acid and liquid introduced into the tank from separator 26 and then facilitating separation of the mixture into two layers. Tank 33 is provided with a valve-controlled draw-off pipe 35 leading from the bottom of the tank.

Example 1.—The oil treated by the process of this example was a petroleum fraction having the following characteristics:

Specific gravity (at 15.5° C.)	0.756
Paraffins	per cent
40 Aromatics	do
Francis bromine No	0.89
Distillation range:	
Start	° C. 96
Dry	° C. 128.5
45 Ratio per cent aromatic bromine No	18.8

A charge of this hydrocarbon oil introduced into still 1 was boiled in the still and the evolved vapors were countercurrently contacted in column 3 with reflux from condenser 4, in which the vapors leaving the top of the column were substantially entirely condensed. Most of the condensate from condenser 4 was returned through valve 5 and pipe 7 to the top of the column to furnish the reflux for the column. The remaining small portion of the condensate was continuously withdrawn through valve 6 and pipe 8 and passed into collecting vessel 9 or 10. The distillation was conducted under substantially atmospheric pressure; i. e., the pressure in condenser 4 and at the top of column 3 was substantially atmospheric and the pressure in still 1 was only enough higher to force the vapor through the rectification column to the condenser.

When the vapor temperature in the top of column 3 reaches 95° C., the condensate passing through pipe 8 is diverted to vessel 10. The cut taken in vessel 10 includes the distillate coming over up to and at a temperature of 111° C. at the top of the column. After this cut has been taken off to vessel 10, the distillation may be discontinued and the residue left in the still withdrawn therefrom. The cut in vessel 9 contains the low boiling fraction of the original oil.

The residue withdrawn from the still contains the high boiling components of that oil. This fraction and residue may be treated or used in any desired manner. The cut taken off to vessel 10 contained 19.25% by volume of aromatics substantially all of which was toluene. It had a Francis bromine number of 0.72. Accordingly, the ratio percent aromatic:bromine number was 28.

This cut was passed through pipe 13 into still 15. There was also charged into still 15 anhydrous methanol in the proportions of 2 parts by volume of methanol for every 1 part by volume of the toluene fraction. The mixture of methanol and toluene fraction was distilled with rectification of the vapors in column 17 and condensation of the vapors leaving the top of the column in condenser 18. Most of the condensate was returned through pipe 19 to the top of column 17 while the remainder was withdrawn through pipe 20.

Toluene and methanol form an azeotrope having a boiling point of 64° C. Hydrocarbons other than toluene present in the toluene fraction introduced into still 15 form azeotropes with methanol which have boiling points below that of the toluene azeotrope. The paraffin hydrocarbons and any small amount of naphthalene hydrocarbons which may have been present in this oil, form azeotropes with boiling points sufficiently below that of the toluene azeotrope for them to be preferentially vaporized and by rectification in column 17 readily separated from the toluene and any toluene-methanol azeotrope which is vaporized in still 15 and enters column 17 so long as there is sufficient methanol present in the vapor and liquid phases in the rectification column so that the temperature at the top of column 17 remains no higher than 64° C. Azeotropes of olefinic hydrocarbons present in the toluene fraction introduced to still 15 will, in substantial part, also be distilled out and carried over with the azeotropes of the paraffin and naphthalene hydrocarbons. Any toluene which may be vaporized in still 15 is largely returned down the rectification column and retained in the still while the azeotropes of the paraffin and naphthalene hydrocarbons and some of the olefin hydrocarbons are distilled out and withdrawn through pipe 20. During this initial distillation stage the condensate withdrawn through pipe 20 is passed through pipe 23 into separator 25. The loss of toluene from the still to the condensate drawn off to separator 25 will depend upon the efficiency with which the vapors are rectified in column 17. Efficient rectification is employed in order to keep down this loss of toluene.

In carrying out the process of this example the initial distillate drawn off through pipe 20 was free from toluene. As the distillation continued, toluene appeared in the distillate and the proportion of toluene to other hydrocarbons gradually increased. The initial distillate was withdrawn to separator 25 after which a cut containing about 91½% by volume of toluene and the remainder substantially olefins (based on the hydrocarbon content of the cut) was taken off to separator 26. The toluene content of the distillate drawn off through pipe 20 rose to about 96% (based on the hydrocarbon content of the distillate) while the cut was being taken off to separator 26.

The distillates thus collected in separators 25 and 26 are treated in the separators with water

to remove methanol from the oil and separated into two layers, a top oil layer and a bottom aqueous methanol layer. The top oil layer withdrawn from separator 25 through pipe 29 is treated or used as desired. This oil layer contains substantially all of the paraffinic and naphthalene constituents of the original toluene fraction introduced to still 15 which boil from the toluene fraction in the absence of an azeotrope at the same or lower temperatures than the toluene boils therefrom. The oil also contains a substantial portion of the olefins contained in the original toluene fraction. The aqueous methanol layer withdrawn from the bottom of separator 25 may be treated to recover the methanol therein for reuse in the distillation of a subsequent batch of toluene fraction in still 15.

The distillate taken off to separator 26 is washed in the separator with water and allowed to form two layers. A bottom aqueous methanol layer is withdrawn through pipe 32 and may be treated with the aqueous methanol from separator 25 as described above. The top oil layer is withdrawn from the separator through pipe 30 and introduced into tank 33. In tank 33 the oil was washed successively six times with 66° Bé sulfuric acid introduced through pipe 34. In each of the washings the oil was treated with 5% by volume of acid, i. e., a total of 30% by volume of the acid was used for washing the oil. After each treatment of the oil with acid the acid containing reaction products of olefins was allowed to settle to the bottom of the tank and withdrawn through pipe 35. This acid may be treated as desired for recovery of any of its constituents or may be discharged as waste. After washing the oil with acid in tank 33 and withdrawal of the last washing acid, the oil thus purified of olefins is withdrawn from the tank through pipe 35, neutralized with an alkali and fractionally distilled, the fraction distilling over at 110.5° C. to 110.7° C. (vapor temperature) being collected separate from the forerunners and higher boiling constituents. The fraction thus recovered was 100% toluene.

In the process of the above example, after the distillation had been carried to the point at which the undistilled residue contained toluene substantially separated from like-boiling paraffinic and naphthalene hydrocarbons, the distillation was continued and the toluene distilled out of that residue and separately collected from the forerunners for treatment with sulfuric acid to remove the olefins which accompanied the toluene. At the conclusion of the distillation of the toluene there was left in still 15 methanol containing a small amount of residual undistilled oil. This methanol may be left in the still and used in distilling a subsequent charge of toluene until the accumulation of impurities in the still residue makes it desirable to withdraw the residue and treat it as desired to recover methanol therefrom for reuse in the distillation of a subsequent charge of toluene fraction.

Instead of continuing the distillation of the toluene fraction after the non-toluene hydrocarbons have been distilled over to leave a residue from which these latter hydrocarbons have been separated to the desired degree as in the above example, the distillation may be discontinued when the unvaporized residue has been substantially freed of paraffinic and naphthalene hydrocarbons boiling in the absence of an azeotropic agent in the same temperature range as the

toluene. This residue, after removing any methanol it may contain by extracting with water, may be treated with sulfuric acid to remove the olefins.

Example 2.—Another oil treated by my process had the following characteristics:

Specific gravity (at 15.5° C.)	0.798
Paraffins	per cent 44.5
Aromatics	do 34.8
Distillation range:	
Start	°C. 62
Dry	°C. 254

The dark color of this oil would interfere with the determination of its bromine number. Accordingly, to determine this bromine number a sample of the oil was treated by the process described in Industrial and Engineering Chemistry, analytical edition 11, 622 (1939), to remove conjugated diolefins by condensation with maleic anhydride followed by extracting the condensation product and excess maleic anhydride from the treated oil sample with 5% aqueous caustic soda solution prior to distilling the treated oil sample as described in this publication. The bromine number for the oil from which conjugated diolefins had thus been removed was determined by the Francis process referred to above. The bromine number was 0.33. Accordingly, the numerical value of the ratio percent aromatic over bromine number of the treated oil was 105.5. The numerical value of this ratio for the original oil prior to removal of the conjugated diolefins would have been somewhat less than 105.5 by an amount corresponding to the increased bromine number of the original oil due to its conjugated diolefin content as compared with the bromine number 0.33 of the oil after treatment to remove the conjugated diolefins.

The oil having the above tabulated characteristics was introduced into still 1 and fractionally distilled in the same manner as the oil of Example 1. The cut coming over in the range 100.2°–110.3° being collected separately from the forerunnings and higher boiling fractions for treatment to recover toluene therefrom. This cut had a toluene content of 25%. It had a Francis bromine number of 0.182. Accordingly, the ratio percent aromatic:bromine number for this cut was 132.

Seven thousand parts by volume of methanol were added to 2710 parts by volume of this cut in still 15 and the mixture distilled through rectification column 17 as described above. When the toluene content of the oil in the distillate had risen to 90% by volume, the succeeding distillate was separately collected until the toluene content of the oil in the distillate from the top of column 17, after passing through a maximum of 100%, fell below 97%. This portion of the distillate, after extracting the alcohol by treatment with water, gave 427 parts by volume of an oil containing 95% by volume of toluene.

This oil was washed three times with 66° Bé. sulfuric acid, an amount of acid equal to 1% of the oil being used for each of the three washings. The acid-washed oil was neutralized. The washing loss was 6% by volume. The separated oil layer was distilled. A fraction of nitration grade toluene, distilling between 110° and 110.7° C. and amounting to 85% of the volume of the distilled oil, was recovered.

Example 3.—Another oil of high aromatic and

olefinic content which was treated by my process had the following characteristics:

Specific gravity (at 15.5° C.)	0.916
Paraffins	per cent 2.0
5 Aromatics	do 49
Distillation range:	

Start	°C. 64
Dry	°C. 349

10 This oil was fractionally distilled as described above, the cut distilling in the vapor temperature range of 95.5–107.7° C. was taken for isolation of toluene. The cut contained 74% toluene by volume and had a Francis bromine number of 0.405. The value for the ratio per cent aromatic:bromine number for the cut was 182.7.

20 Five thousand parts by volume of methanol were added to 1250 parts by volume of this cut in still 15 and the mixture distilled through a rectification column 17 as described above. When the toluene content of the oil in the distillate had risen to 97% by volume, the succeeding fractions were separately collected until the toluene content of the distillate oil, after passing through a maximum of 100%, fell below 99%. A total of 25 362 parts by volume of distillate oil was collected in this cut, the oil containing 99% by volume of toluene.

30 This oil was washed twice with 66° Bé. sulfuric acid and neutralized, a volume of acid equal to 1% of the oil being used for each washing. The washing loss was 3% by volume. The separated oil layer was distilled and yielded 92% of its volume as a fraction distilling between 110.0–110.5° C. vapor temperature of high grade industrial toluene.

35 The invention described above is of particular importance as a method for the recovery of pure toluene from oil fractions containing it together with substantial quantities of olefins and other non-toluene hydrocarbons.

40 Toluene may be recovered by subjecting to the azeotropic distillation step of my process an oil containing, in addition to like-boiling, non-aromatic hydrocarbons, lower and higher boiling aromatic and non-aromatic hydrocarbons. In azeotropically distilling such an oil, the distillation is continued until the residue contains toluene and no more than 10 parts of like-boiling paraffinic and naphthenic hydrocarbons (i. e., paraffinic and naphthenic hydrocarbons which, in the absence of an azeotropic agent, boil from the oil in the same temperature range as the toluene boils therefrom). The toluene thus separated from these like-boiling hydrocarbons is separated from olefins by treatment with sulfuric acid and may be separated from higher boiling aromatic and non-aromatic hydrocarbons by a non-azeotropic fractional distillation.

45 It is, nevertheless, of particular advantage in the recovery of toluene to preliminarily distill the original toluene-containing oil taking off a cut having an end boiling point but little above the boiling point of toluene; i. e., an end boiling

50 point of 118° C. and preferably of 111° C. By so doing there will be excluded from the toluene fraction subsequently subjected to azeotropic distillation a large part or all of the non-toluene hydrocarbons boiling from the toluene oil at 55 temperatures above the boiling point of toluene, the completeness of their separation depending on the sharpness of fractionation during the distillation and the relative amounts and kinds of the oil constituents. In the azeotropic distillation of such a fraction a residue is obtained

largely or wholly freed of paraffins and naphthenes. By washing such a residue with sulfuric acid to remove its olefin content a toluene product of 95% or higher purity may be directly obtained, or toluene of substantially 100% purity may be obtained by a final fractional distillation of the sulfuric acid-washed oil.

While so far as recovering pure toluene is concerned it is not so important in the preliminary fractional distillation of the toluene oil to exclude forerunnings boiling substantially below the boiling point of the toluene as it is to exclude materials boiling higher than toluene, it is economically desirable to exclude forerunnings high in non-toluene hydrocarbons for the reasons pointed out above. In general, it is preferred to subject to the azeotropic distillation a toluene cut boiling in the range 95° to 118° C., preferably in the range 95° to 111° C.

The process of this invention may likewise be applied to the recovery of other aromatics from oil fractions containing them together with non-aromatic constituents boiling from the oil fraction in the same temperature range as the aromatic hydrocarbon or hydrocarbons which are to be recovered boil therefrom. In recovering benzene it is preferred to subject to azeotropic distillation an oil fraction boiling in the range about 65° to about 80° C. For the recovery of a mixture of xylenes it is preferred to azeotropically distill a xylene fraction boiling in the range about 125° to about 145° C. It is particularly desirable, in recovering aromatic hydrocarbon, to exclude high boiling hydrocarbons from the oil fraction subjected to the azeotropic distillation step of my process as discussed above in connection with the recovery of toluene. Accordingly, in all cases I prefer that the oil fraction azeotropically distilled be one having an end boiling point in degrees Centigrade which is not more than 1.06 times the boiling point in degrees Centigrade of the aromatic hydrocarbon or hydrocarbons in the oil fraction which are to be recovered in the residue of the azeotropic distillation. Following azeotropic distillation of an oil fraction having this end boiling point, the residue of the azeotropic distillation may be treated with sulfuric acid, to remove therefrom the olefins, and then distilled to recover the aromatic hydrocarbon as a product of the desired purity.

The amount of acid used for washing the aromatic concentrate to remove olefins depends upon the oil fraction treated by my process. The amount may be calculated by estimating the quantity of olefins to be removed, e. g., by determining the bromine number, and washing the oil with somewhat more than the theoretical amount of sulfuric acid required for reaction with the olefins. As a general rule, by observing, after each washing, the color and volume of the acid sludge as compared with the volume of the acid added, one may judge when the olefins have been removed by the sludge having a light color and being of substantially the same volume as the acid. Acids of a concentration of 88% or higher, particularly about 93% acid, may be satisfactorily used for washing the oil at room temperatures.

As azeotropic agents in the distillation of the hydrocarbon fractions, I may employ any material which forms azeotropes with the like-boiling paraffinic or naphthenic hydrocarbons present in the aromatic fraction. I have found methanol to be particularly suitable for use as

the azeotropic agent, although the invention is not limited to any particular azeotropic agent. The following materials are representative of those which may be used as azeotropic agents in carrying out the azeotropic distillation step of my invention: aliphatic monohydroxy alcohols containing no more than 5 carbon atoms to the molecule; i. e., methanol, ethanol, primary and secondary propanol, the butanols and the amyl alcohols (aqueous as well as non-aqueous alcohols may be used); acetic acid and acetic anhydride; pyridine, para-dioxane, ethylene chlorhydrin, ethyl aceto-acetate with water, methyl lactate, allyl alcohol; ketones with water, such as acetone, methyl ethyl ketone or diethyl ketone and water; and ethers of ethylene glycol, such as the mono-ethyl, mono-butyl, or mono-ethyl ether of ethylene glycol.

The azeotropic distillation is carried out with rectification of the vapors in the presence of the azeotropic agent until the unvaporized residue contains no more than 10 parts by weight of like-boiling paraffinic and naphthenic hydrocarbons for every 90 parts by weight of the aromatic hydrocarbon which it is desired to recover.

While I have described my process in conjunction with an example in which two distillation steps are carried out as batch procedures, either or both of these distillations advantageously may be carried out continuously by well known continuous distillation procedures suitable for the fractional distillation of mixtures of two or more liquids. In the azeotropic distillation of the aromatic oil fraction side streams enriched in aromatics as compared with the top product may be drawn off from the fractionating column, particularly from the lower part of the column. The term "residue" in this specification and the appended claims is used in a broad sense to include such side streams.

It is, of course, obvious a preliminary distillation of a crude aromatic oil to recover a fraction suitable for recovery of the desired aromatic therefrom by azeotropic distillation and removal of olefins by means of sulfuric acid need not be carried out in immediate conjunction with the azeotropic distillation of the aromatic fraction. For example, the aromatic fraction suitable for treatment by the azeotropic distillation and sulfuric acid washing steps of my process may be produced in one plant and transported to and treated later in another plant by these latter two steps.

In this specification I have described the azeotropic distillation of aromatic oil fractions as carried out under substantially atmospheric pressure. It is, of course, possible to carry out either the non-azeotropic fractional distillation or the distillation with the azeotropic agent under pressures above or below atmospheric. In such cases the particular temperatures in the distillations will correspond to the change in distillation temperatures with the change in pressure. The temperatures given in this specification and in the appended claims are corrected temperatures for one atmosphere pressure (760 mm. of Hg). I have used the term "aromatic hydrocarbon" in a broad sense to include both chemical individuals such as toluene, and aromatic fractions of limited boiling range containing closely related and difficultly separable aromatic compounds which are commercially used as a unit such as "xylol" which may contain two or more of the isomeric xylenes and ethyl benzene.

I claim:

1. The process for the recovery of a nitration-pure aromatic hydrocarbon of the benzene series from an oil containing the same and containing higher, lower and like-boiling, non-aromatic hydrocarbons, including a substantial proportion of like-boiling olefins, which comprises fractionally distilling said aromatic oil and in this distillation taking off an oil fraction having an end boiling point in degrees centigrade not more than 1.06 times the boiling point in degrees centigrade of said aromatic hydrocarbon and containing said aromatic hydrocarbon and olefins in amount such that the numerical value of the ratio per cent aromatic:bromine number for said oil fraction is less than 250, azeotropically distilling said oil fraction with fractionation of the distilled vapors in the presence of a material forming low-boiling azeotropes with the non-aromatic hydrocarbons present in said fraction, in said azeotropic distillation taking off as an overhead distillate with said material substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid of a concentration and in an amount such that the aromatic hydrocarbon fraction is substantially completely freed of olefins, separating the acid-washed aromatic hydrocarbon fraction from reaction products of the sulfuric acid and olefins, neutralizing the aromatic hydrocarbon fraction with an alkali and fractionally distilling the neutralized fraction and in this distillation collecting separate from forerunnings and higher boiling residue a fraction consisting of nitration-pure aromatic hydrocarbon.

2. The process for the recovery of a nitration-pure aromatic hydrocarbon of the benzene series from an oil containing the same and containing higher, lower and like-boiling, non-aromatic hydrocarbons, including a substantial proportion of like-boiling olefins, which comprises fractionally distilling said aromatic oil and in this distillation taking off an oil fraction having an end boiling point in degrees centigrade of said aromatic hydrocarbon and containing said aromatic hydrocarbon and olefins in amount such that the numerical value of the ratio per cent aromatic:bromine number for said oil fraction is less than 250, azeotropically distilling said oil fraction with fractionation of the distilled vapors in the presence of an aliphatic monohydroxy alcohol containing no more than 5 carbon atoms to the molecule, said alcohol forming low-boiling azeotropes with the non-aromatic hydrocarbons present in said fraction, in said azeotropic distillation taking off as an overhead distillate with said alcohol substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid of a concentration and in an amount such that the aromatic hydrocarbon fraction is substantially completely freed of olefins, separating the acid-washed aromatic hydrocarbon fraction from reaction products of the sulfuric acid and olefins

and olefins, neutralizing the aromatic hydrocarbon fraction with an alkali and fractionally distilling the neutralized fraction and in this distillation collecting separate from forerunnings and higher boiling residue a fraction consisting of nitration-pure aromatic hydrocarbon.

3. The process for the recovery of nitration-pure toluene from an oil containing the same and containing higher, lower and like-boiling, non-aromatic hydrocarbons, including a substantial proportion of like-boiling olefins, which comprises fractionally distilling said aromatic oil and in this distillation taking off an oil fraction boiling in the range 95° C. to 111° C. containing toluene, like-boiling non-aromatic hydrocarbons and like-boiling olefins in amount such that the numerical value of the ratio per cent aromatic:bromine number for said oil fraction is less than 250, azeotropically distilling said oil fraction with fractionation of the distilled vapors in the presence of methanol, said methanol forming low-boiling azeotropes with the non-aromatic hydrocarbons present in said fraction, in said azeotropic distillation taking off as an overhead distillate with said methanol substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid of a concentration and in an amount such that the aromatic hydrocarbon fraction is substantially completely freed of olefins, separating the acid-washed aromatic hydrocarbon fraction from reaction products of the sulfuric acid and olefins, neutralizing the aromatic hydrocarbon fraction with an alkali and fractionally distilling the neutralized fraction and in this distillation collecting separate from forerunnings and higher boiling residue a fraction consisting of nitration-pure aromatic hydrocarbon.

4. The process for the recovery of a nitration-pure aromatic hydrocarbon of the benzene series from an oil containing the same and containing higher, lower and like-boiling, non-aromatic hydrocarbons, including a substantial proportion of like-boiling olefins, which comprises fractionally distilling said aromatic oil and in this distillation taking off an oil fraction having an end boiling point in degrees centigrade not more than 1.06 times the boiling point in degrees centigrade of said aromatic hydrocarbon and containing said aromatic hydrocarbon and olefins in amount such that the numerical value of the ratio per cent aromatic:bromine number for said oil fraction is less than 250, azeotropically distilling said oil fraction with fractionation of the distilled vapors in the presence of a ketone and water, said ketone and water forming low-boiling azeotropes with the non-aromatic hydrocarbons present in said fraction, in said azeotropic distillation taking off as an overhead distillate with said ketone and water substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the like-boiling olefins which were present in said oil fraction, washing said aromatic hydrocarbon fraction with sulfuric acid of a concentration and in an amount such that the aromatic

15

hydrocarbon fraction is substantially completely freed of olefins, separating the acid-washed aromatic hydrocarbon fraction from reaction products of the sulfuric acid and olefins, neutralizing the aromatic hydrocarbon fraction with an alkali and fractionally distilling the neutralized fraction and in this distillation collecting separate from forerunnings and higher boiling residue a fraction consisting of nitration-pure aromatic hydrocarbon.

5. The process for the recovery of a nitration-pure aromatic hydrocarbon of the benzene series from an oil containing the same and containing higher, lower and like-boiling, non-aromatic hydrocarbons, including a substantial proportion of like-boiling olefins, which comprises fractionally distilling said aromatic oil and in this distillation taking off an oil fraction having an end boiling point in degrees centigrade not more than 1.06 times the boiling point in degrees centigrade of said aromatic hydrocarbon and containing said aromatic hydrocarbon and olefins in amount such that the numerical value of the ratio per cent aromatic:bromine number for said oil fraction is less than 250, azeotropically distilling said oil fraction with fractionation of the distilled vapors in the presence of methyl ethyl ketone and water, said ketone and water forming low-boiling azeotropes with the non-aromatic hydrocarbons present in said fraction, in said azeotropic distillation taking off as an overhead distillate with said ketone and water substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid of a concentration and in amount such that the aromatic hydrocarbon fraction is substantially completely freed of olefins, separating the acid-washed aromatic hydrocarbon fraction from reaction products of the sulfuric acid and olefins, neutralizing the aromatic hydrocarbon fraction with an alkali and fractionally distilling the neutralized fraction and in this distillation collecting separate from forerunnings and higher boiling residue a fraction consisting of nitration-pure aromatic hydrocarbon.

6. The process for the recovery of nitration-pure toluene from an oil containing the same and containing higher, lower and like-boiling, non-aromatic hydrocarbons, including a substantial proportion of like-boiling olefins, which comprises fractionally distilling said aromatic oil and in this distillation taking off an oil fraction boiling in the range 108.2° C. to 111° C. containing toluene, like-boiling non-aromatic hydrocarbons and like-boiling olefins, azeotropically distilling said oil fraction with fractionation of the distilled vapors in the presence of methanol, said methanol forming low-boiling azeotropes with the non-aromatic hydrocarbons present in said fraction, in said azeotropic distillation taking off as an overhead distillate with said methanol substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid

75

of a concentration and in amount such that the aromatic hydrocarbon fraction is substantially completely freed of olefins, separating the acid-washed aromatic hydrocarbon fraction from reaction products of the sulfuric acid and olefins, neutralizing the aromatic hydrocarbon fraction and fractionally distilling the neutralized fraction and in this distillation collecting separate from forerunnings and higher boiling residue a fraction consisting of nitration-pure aromatic hydrocarbon.

7. The process for the recovery of pure toluene from an oil containing the same and containing higher, lower and like-boiling, non-aromatic hydrocarbons, including a substantial proportion of like-boiling olefins, which comprises fractionally distilling said aromatic oil and in this distillation taking off an oil fraction in which toluene is concentrated accompanied by like-boiling, non-aromatic hydrocarbons and like-boiling, olefins, azeotropically distilling said oil fraction with fractionation of the distilled vapors in the presence of methanol, said methanol forming low-boiling azeotropes with the non-aromatic hydrocarbons present in said fraction, in said azeotropic distillation taking off as an overhead distillate with said methanol substantially all of the like-boiling and lower boiling non-aromatic hydrocarbons other than olefins and a portion of the olefins present in said oil fraction, thereby recovering an aromatic hydrocarbon fraction containing said toluene and a portion only of the olefins which were present in said oil fraction, washing said aromatic hydrocarbon fraction with sulfuric acid of a concentration and in amount such that residual olefins not separated from the toluene by the azeotropic distillation are removed from the aromatic hydrocarbon fraction, neutralizing the acid-washed aromatic hydrocarbon fraction and fractionally distilling the neutralized fraction and in this distillation collecting separate from other constituents of said acid-washed aromatic hydrocarbon fraction a distillate fraction which is substantially free from olefins and has a specific gravity of nitration-grade toluene.

8. The process for the recovery of a pure aromatic hydrocarbon having a boiling point up to and including the boiling points of the xylenes from an oil containing the same and containing higher, lower and like-boiling, non-aromatic hydrocarbons, including a substantial proportion of like-boiling olefins, which comprises fractionally distilling said aromatic oil and in this distillation taking off an oil fraction in which said aromatic hydrocarbon is concentrated accompanied by like-boiling, non-aromatic hydrocarbons and like-boiling olefins, azeotropically distilling said oil fraction which fractionation of the distilled vapors in the presence of an aliphatic alcohol containing 1 to 3 carbon atoms in the molecule, said alcohol forming low-boiling azeotropes with the non-aromatic hydrocarbons present in said fraction, in said azeotropic distillation taking off as an overhead distillate with said alcohol substantially all of the like-boiling and lower boiling non-aromatic hydrocarbons other than olefins and a portion of the olefins present in said oil fraction, thereby recovering an aromatic hydrocarbon fraction containing said aromatic hydrocarbon and a portion only of the olefins which were present in said oil fraction, washing said aromatic hydrocarbon fraction with sulfuric acid of a concentration and in amount such that residual olefins not separated from said aromatic

hydrocarbon by the azeotropic distillation are removed from the aromatic hydrocarbon fraction, neutralizing the acid-washed aromatic hydrocarbon fraction and fractionally distilling the neutralized fraction and in this distillation collecting separate from other constituents of said acid-washed aromatic hydrocarbon fraction a distillate fraction which is substantially free from olefins and has a specific gravity of said aromatic hydrocarbon of nitration-grade.
